United States Patent Office

Des. 195,503
Patented June 25, 1963

195,503

RESTAURANT BUILDING

Robert L. Fellers, Lawrence, Kans., assignor to Griff's of America, Inc., Kansas City, Mo., a corporation of Missouri

Filed May 21, 1962, Ser. No. 70,218

Term of patent 14 years

(Cl. D13—1)

Fig. 1.

Fig. 2.

Fig.3.

Fig.4.

Fig.5.

FIG. 1 is a front perspective view of a restaurant building showing my new design;

FIG. 2 is a side elevation view thereof showing the side opposite to that shown in FIG. 1;

FIG. 3 is a front elevation view thereof;

FIG. 4 is a rear elevation view thereof; and

FIG. 5 is an enlarged transverse cross-sectional view through a portion of the side wall.

I claim:

The ornamental design for a restaurant building, as shown,
